SHOCKPROOF PARACHUTE HARNESS

James H. Strong, Windsor, N. J.

Application August 13, 1940, Serial No. 352,445

4 Claims. (Cl. 244—151)

This invention relates to the harness worn by parachute jumpers to which the parachute is attached whereby the jumper is suspended from the parachute after the latter has opened in the air, and the object of the invention is to utilize resilient members of the harness to reduce the shock upon the jumper when the parachute first opens after the jumper drops from the airplane or balloon which brought him off the ground.

Parachutes of the pack type designed to be worn upon the back of the user, or upon which the user sits when in the aircraft, are connected to the portions of the harness which encircle the body of the user and support his weight in the air by "risers" or "lift webs," to the free ends of which the parachute shrouds are attached. My invention contemplates the utilization of rubber or other resilient material for a portion of the lift webs and consists in the adaptation of such material to known types of harness, and in the details of construction hereinafter described.

Further aims and characteristics of the invention appear in connection with the following description of the illustrative embodiment shown in the drawing, and what the invention comprises is stated in the appended claims.

In the drawing,

Figs. 1 and 2 are respectively a front view and a back view of a parachute harness embodying the invention in the position in which it is worn, showing it detached from the parachute;

Fig. 3 is a side view of the upper part of the harness, drawn to a larger scale, showing the parachute pack in position on the back pad of the harness;

Figs. 4, 5 and 6 are enlarged views of the resilient shock relieving sections, Fig. 4 being a cross-section on the line 4—4 in Fig. 5, Fig. 5 being a cross-section on the line 5—5 in Fig. 6, and Fig. 6 being a cross-section on the line 6—6 in Figs. 5, respectively, and

Fig. 7 is an enlarged cross-section of one of the fittings for connecting the body strap with the lift web loops.

In the standard military parachute, the harness which supports the user in the air comprises lift webs or risers which are made of two webbing strips arranged parallel to each other and which pass around the body of the user when wearing the harness over his shoulders to connect with the parachute on his back or thereabouts in the normal wearing position. These lift webs support him in a sitting position from the opened parachute trailing above during the descent. Usually a pad is placed on the user's back to

which the lift webs are loosely connected by cloth or leather clips fitted with snap fasteners or other quick detachable means to permit them to be jerked loose when the parachute opens. Thus 5 the shock on the user when the parachute opens is severe, and the consequences sometimes are serious.

In the improved harness shown in the drawing, the lift webs 11, although they are continuous around the lower end of the user's body, are each provided on each side in front of the wearer's shoulders with loop portions 12 (see Fig. 3) which are connected to upper and lower links 13, 14 by strips 15, and are doubled back around the user's shoulders to be out of the way in normal wearing position. These upper and lower links 13, 14, are also connected to each other by extensible shock absorbing members 16. In the harness illustrated, these shock absorbing members 16 10 are rubber cords, three each being used for each run of the lift web, and they are looped at their ends over the adjacent branches of the links 13, 14 and secured by lashings 17, as shown in Fig. 6. These rubber cords are advantageously covered by 15 a tubular fabric housing 18, made of waterproof cloth and closed along one longitudinal side by a talon fastener 19 of the well known zipper type.

A fabric tie 20, secured by a snap fastener 21 20 holds the adjacent exposed loop 12 to the rear side of the housing 18 in wearing position. Similar fastenings 22, 23 are provided for loosely securing the loops 12 and lift webs 11 to the back pad 24 beneath the parachute pack 25. These fastenings readily break loose to free the loops when 25 the shock of opening the parachute comes on the lift webs, stretching the resilient members 16, and the length of the loops is made adequate to suit the maximum extension of the members 16, so that no shock comes upon the wearer. These 30 resilient members 16 pull out of the ends of their covers 18 readily without loosening the talons 19 and the loops 12 are entirely free to accommodate whatever movements the ends of the resilient members assume under the force exerted by the 35 parachute upon the lift webs. Should either of these members 16 break on the opening of the parachute, the weight of the user would be sustained by the loop portions 12 of the lift webs.

The back pad 24 and leg loop straps 26, 27, 40 are secured in place on the wearer by means of two body straps 28, one of which has a D link 29 to receive the snap hook 30 on the leg strap 26, and the other of which has a snap hook 31 to engage the D link 32 on the leg strap 27. The 45 body straps are secured near each end to the

adjacent run of the lift webs 11, passing between the two parallel webs and around behind the back of the wearer outside of the back pad and crossing in the upper middle of the back as shown in Fig. 2, continuing over the wearer's shoulders and down along the under sides of the adjacent loops 12 of the lift webs to which each is loosely secured by passing between them, the webs being secured together above and below the body straps, as shown in Fig. 1, and the adjacent overlapping ends of the body straps pass around the wearer's waist and are loosely secured to the outer side of the back pad near its lower end by a fabric loop 33. Similar loops 34 secure the body straps to the back pad where they cross near the top of the pad, the two portions of the straps which cross being loosely secured together by loops 35 secured thereto, as shown in Fig. 2.

A snap hook 36 and D link 37 are run on each body strap 28 on each side in front near the waist line for hooking these two parts together to form a belt around the waist of the wearer. The body straps are also adjustably secured to the loops 12 near their lower ends in front by cross bar links 38, as shown in Figs. 3 and 7, thus enabling the position of the looped lift webs and resilient members 16 to be adjusted up and down on the chest of the wearer to suit different individuals. The length of each body strap as a whole make likewise be adjusted to suit the wearer by taking in or letting out the overlapping waist sections 39 by means of the adjustable cross bar links 40, to which their ends are secured.

The ends of the lift webs or risers 11 are fitted with D links 41 and are passed into the pack 25, where they are connected to the shrouds 42 in the usual manner, and the parachute canopy and shrouds are folded into the pack, which is provided with a quick release device of any suitable type.

Readily detachable means may be provided for securing the pack to the pack pad, such as the fabric ties 43 provided with snap fasteners 44, as shown in Fig. 3. The quick release device, tripped by a cord 45, enables the parachute to be freed from the pack as is usual in this type of parachute. The resilient members in the lift webs in no way interfere with the normal operation of opening the packed parachute.

The action of the harness is the same as that of the standard harness excepting that there is no shock upon the user when the parachute opens, due to the stretching of the rubber cords, and the easy action eliminates bruises and sprains not unusual with the standard harness, thereby en-

abling parachutes to be used for regular air transportation in addition to emergency landings.

The invention is not restricted to the details of construction illustrated, but what is claimed is as follows:

1. A parachute harness comprising lift webs connected to the parachute shrouds, parallel loops in said lift webs, and resilient shock absorbing members extending along said loops and connecting the points of attachment of said loops to said lift webs, said resilient members being disposed in the portions of the harness overlying the chest of the wearer, and detachable fastenings securing said resilient members to the adjacent harness portions, respectively, whereby said resilient members are released from said harness under the stress due to opening the parachute in the normal operation of the apparatus.

2. A parachute harness comprising lift webs connected to the parachute shrouds, parallel loops in said lift webs, and resilient shock absorbing members extending along said loops and connecting the points of attachment of said loops to said lift webs, said loops being doubled and folded back on the lift webs over the shoulders of the wearer, and detachable fastenings securing said doubled back loop portions to the lift webs on the back of the wearer, respectively, whereby said lift webs are secured in normal position and are free to assume full extended position upon the opening of the parachute to which said shrouds are connected.

3. In a parachute harness for use with a packed parachute carried behind the wearer, lift webs passing from behind over the wearer's shoulders and chest, said lift webs having parallel loop portions doubled back over the wearer's shoulders and detachably secured to adjacent back portions of the harness, and resilient members of less length than said loop portions extending along said line, and connecting the ends thereof and disposed in front of the wearer's chest.

4. In a parachute harness for use with a packed parachute carried behind the wearer, lift webs passing from behind over the wearer's shoulders and chest, said lift webs having loop portions doubled back over the wearer's shoulders, and resilient members of less length than said loop portions connecting the ends thereof and disposed in front of the wearer's chest, said resilient members being protected by tubular fabric housings loosely secured to said loop portions and open at the end to permit said resilient members to be withdrawn therefrom.
